(57) **CLAIM**

I claim the ornamental design for a foot for audio equipment, as shown and described.

DESCRIPTION

FIG. 1 is a top, front, and right side perspective view of the first embodiment of a foot for audio equipment showing my new design;

FIG. 2 is a perspective view of the bottom, rear, and left side of the foot for audio equipment of FIG. 1;

FIG. 3 is a front elevational view of the foot for audio equipment of FIG. 1;

FIG. 4 is a rear elevational view of the foot for audio equipment of FIG. 1;

FIG. 5 is a right side elevational view of the foot for audio equipment of FIG. 1, the left side elevational view being a mirror image thereof;

FIG. 6 is a top plan view of the foot for audio equipment of FIG. 1;

FIG. 7 is a bottom plan view of the foot for audio equipment of FIG. 1;

FIG. 8 is a top, front, and right side perspective view of the second embodiment of the foot for audio equipment showing my new design;

FIG. 9 is a perspective view of the bottom, rear, and left side of the foot for audio equipment of FIG. 8;

FIG. 10 is a front elevational view of the foot for audio equipment of FIG. 8;

FIG. 11 is a rear elevational view of the foot for audio equipment of FIG. 8;

FIG. 12 is a right side elevational view of the foot for audio equipment of FIG. 8, the left side elevational view being a mirror image thereof;

FIG. 13 is a top plan view of the foot for audio equipment of FIG. 8; and,

FIG. 14 is a bottom plan view of the foot for audio equipment of FIG. 8.

The broken lines in the drawings show portions of the foot for audio equipment that form no part of the claimed design.

1 Claim, 10 Drawing Sheets
